Primary Examiner — Rhea Shields

(74) Attorney, Agent, or Firm — MALLOY & MALLOY,
PL(57) **CLAIM**

The ornamental design for an eyewear package, as shown and described.

DESCRIPTION

FIG. 1 is a front perspective view of our design for eyewear package;

FIG. 2 is a front view thereof;

FIG. 3 is a left side view thereof;

FIG. 4 is top view thereof;

FIG. 5 is a right side view thereof;

FIG. 6 is bottom view thereof;

FIG. 7 is a rear view thereof; and,

FIG. 8 is an exploded, front perspective view thereof.

The broken line showing of the hanger, folded insert, and eyeglasses are for the purpose of illustrating environmental structure and form no part of the claimed design.

1 Claim, 8 Drawing Sheets# US D1,005,842 S
